FRAUD DETECTING DEVICE FOR COIN
CONTROLLED APPARATUSThomas R. Freeman and Willard S. Freeman,
Washington, D. C.

Application November 20, 1937, Serial No. 175,716

7 Claims. (Cl. 194—97)

This invention relates to a device for preventing fraud during the operation of coin-controlled mechanisms.

An object of the invention is the provision of a device which is adapted to be attached to the coin-controlled box of a telephone or other similar coin-controlled mechanism to prevent a party from operating the telephone by means of slugs or improper types of coins whereby the proper coin must be deposited before the coin can be dropped into the usual slot of the telephone receiver.

Another object of the invention is the provision of a device for determining in advance whether the coin is the right type for operating a coin-controlled mechanism before the coin can be deposited in the usual slot which sets the mechanism in operation, the device including means which will receive the coin for presenting one face of the coin to a plurality of projections which are moved into engagement with the coin and if the coin is of the proper type these projections will cause mechanism to release the coin for depositing in the regular slot of the coin-controlled mechanism.

A further object of the invention is the provision of a device which is adapted to be used in connection with a coin-controlled mechanism for preventing the coin or slug from being deposited in the usual slot of the housing for the coin-controlled mechanism and in which one face of the coin, due to its peculiar configuration, will be engaged by a plurality of projections which, if the coin is of the proper type, will set mechanism in operation for releasing the coin for deposit in the slot of the housing of the coin-controlled mechanism, means being employed for ejecting spurious coins to permit others to insert coins of the proper type.

This invention will be best understood from a consideration of the following detailed description, in view of the accompanying drawings forming a part of the specification; nevertheless, it is to be understood that the invention is not to be confined to the disclosure, being susceptible of such changes and modifications as define no material departure from the salient features of the invention as expressed in the appended claims.

In the drawings:

Figure 1 is a longitudinal vertical section of a coin detecting mechanism in an inoperative position and constructed in accordance with the principles of our invention,

Figure 2 is a similar vertical section showing

the mechanism in an operative position for detecting a coin,

Figure 3 is a section similar to that shown in Figs. 1 and 2 showing the mechanism moving from an operative to an inoperative position, 5

Figure 4 is a transverse vertical section taken along the line 4—4 of Figure 1,

Figure 5 is a transverse vertical section taken along the line 5—5 of Fig. 1,

Figure 6 is a transverse vertical section taken along the line 6—6 of Fig. 1,

Figure 7 is a fragmentary view in elevation of the front of the device,

Figure 8 is a top plan view of the same,

Figure 9 is a horizontal section taken along the line 9—9 of Fig. 1,

Figure 10 is a vertical section of a cylinder piston for preventing too rapid movement of the raising of the spring-actuated top of the casing,

Figure 11 is a bottom plan view of a plurality 20 of coin-detecting bars,

Figure 12 is a bottom plan view of a plurality of controlling bars,

Figure 13 is a view in perspective of the controlling bars in assembled relation, 25

Figure 14 is a view in perspective of the coin-detecting bars and the controlling bars showing mechanism for cooperatively operating the groups of bars, and

Figure 15 is a fragmentary longitudinal vertical section of the bottom of the casing showing the parts in position for removal of a slug or improper coin.

Referring more particularly to the drawings, 30 10 designates generally a housing having a rear wall 11, bottom portion 12, a shelf or slide 13 and a front plate 14. The housing also includes a pair of shelves 15 and 16 connected together by a depending member 17. A plate 18 depends from the front end of the shelf 16 and in cooperation with a plate 19 forms a coin slot 20. The elements just described are connected to the side walls 21 and 21a of the housing 10.

The housing is provided with a cover plate 25 which is pivoted at 26 to the upper rear edge 45 of the wall 11. A spring 27 tends at all times to move the cover 25 upwardly and away from the upper end of the housing. The cover is provided with a depending member 28 which is located at approximately a right angle to the cover per se and a portion of the cover extends at right angles from the lower edge of the section 28 as indicated at 29. A lip or finger-piece 30 projects from the free end of the section 29. The last-mentioned section is provided with a 50

coin slot 31 which is adapted to align with the slot 20.

5 A reciprocating rod 32 is mounted in an opening 33 in a slideable plate 34 on the top of the shelf 16 and a flange 14a projecting inwardly from the front plate 14. The lower end of the rod is received and guided by passages 35 and 36 respectively formed in members 37 and 38 forming the front part of a slideable drawer, generally 10 designated by the numeral 39, which is located between the partition 13 and the bottom 12. An arm 40 extends at an acute angle upwardly and inwardly from the rod 32 and is provided with a horizontal extension 41. A pin 42 is secured 15 to the horizontal extension 41 and extends through an opening 43 in the section 29 of the top 25 and has an enlargement 44 adapted to engage the outer surface of the section 29 so that when the cover is raised by the spring 27 the reciprocating rod 32 will be elevated. The opening 20 43 is slightly larger than the pin 42 to provide for sufficient play of the pin in said opening when the top 25 is oscillated.

25 A cylinder 45, shown more particularly in Fig. 10, is secured to the front wall 14 of the housing 10 and is provided with an air vent 46 normally closed by a valve 47 which will permit air to enter said cylinder when a piston 48 is elevated by means of a rod 49 connected to the horizontal extension 41. The piston 48 is adapted to prevent rapid upward or downward movement of the top in order to give the moving elements sufficient time to perform their functions.

35 A shaft 50 has its outer end located within a bushing 51 which in turn is secured by means of an integrally formed plate 52 to the front wall 14. This bushing extends through an opening 53 formed in said wall. A coil spring 54 surrounding the shaft 50 presses against a collar 55 formed on the shaft 50 and against the rear wall of a pocket 56 in the bushing for urging the shaft to the right, as shown in Figs. 1 to 3, inclusive.

45 A conically-shaped member 57 is also connected to the shaft 50 and is adapted to be engaged by a cam member 58 connected to the reciprocating rod 32. An elongated toothed wheel 59 is connected to the shaft 50 at the inner end and a coin-supporting plate 60 is secured to the inner end of the wheel. A rack 61, shown in Fig. 9, engages the elongated teeth of the wheel 59 so that when the rod 32 is reciprocated the wheel 59, shaft 50 and the coin-supporting disc 60 will also be revolved.

55 The disc 60 is provided with a peripheral flange 62 which is adapted to engage the angular edge of the outer face of the coin for retaining the coin in proper position. The outer edge of the disc is provided with an annular lip 63 for a purpose which will be presently explained.

60 A plurality of coin-detecting bars 70, shown more particularly in Fig. 14, which are considerably restricted in thickness, are placed in flat contact with each other and are guided by a frame secured to the side walls of the housing 65 10. This frame consists of a top bar 71 which extends entirely across the housing and a pair of depending members 72 which engage the outer faces of the end bars. The members 72 retain the bars in close association at all times.

70 Each of the bars 70 is provided with cut-out portions 73 and these cut-out portions are adapted to be aligned to receive the cross bar 71 of the frame. These cut-out portions provide front fingers 74 and rear fingers 75 and 76 with the 75 finger 76 of less width than the finger 75 so that

the front faces of the finger 76 are spaced rearwardly of the front faces of the fingers 75 for a purpose which will be presently explained.

Each bar 70 has a reduced rearward extension 71 or 78 and the rear ends are provided with passages 79 or 80 (Fig. 3). A slot 81 extends through the upper edge of each extension into its respective opening 79 or 80. 5

A shaft 82 is supported by the side walls of the housing 10 and a plurality of weights 83 and 84 are pivotally mounted on said shaft. The weight 83 has a finger 85 projecting in through the slot 81 of the opening 79 while a finger 86 projecting from a weight 84 projects through a slot 81 into an opening 80 in the extension 78. It will be noted that not only the openings 79 and 80 are staggered in alternate relation but the slots 81 and the weights 83 and 84 are also staggered in the same relation.

A plurality of control bars 90 and 91 are slidably mounted on the shelf 15 (Figs. 1 to 3, inclusive, and Figs. 13 and 14). A pair of posts 92 extend upwardly from the shelf 15 and embrace the outer face of the two end bars 90 and 91 and maintain the bars in flat contact with each other. 20

Each bar 90 is provided with an opening 93 and a slot 94 extends from this opening to the outer lower edge of an extension 95 projecting from the bar 90. Each of the control bars 91 is provided with an extension 96 having an opening 97 and a slot 98. Each weight 93 at its upper end and in a line with the finger 85 or 86, as the case may be, is provided with a finger 99 or 100 which is adapted to be received respectively in the slot 94 or the slot 98 so that these fingers project into their respective openings 93 or 97. Thus it will be seen that when the weights 83 are moved backwardly at their upper ends that the sliding movement of the control bars 90 and 91 will cause a complementary movement of the 40 bars 70 or vice versa. It will be noted that the openings 93 and 97 are staggered in alternate bars in the same relation as are the openings 79 and 80 in the respective extensions 77 and 78 of the bars 70. This alternate arrangement places alternate slots in both the extensions 77 and 78 and 45 95 and 96 against a flat portion of said extension to prevent the fingers at the opposite ends of the weights 83 and 84 from engaging the edges of adjacent slots and thus prevent the proper operation of the weights and likewise the bars 70, 90 and 91.

It will be noted that the front ends of the bars 90 recede slightly from the front ends of the bars 91 so that the alternate bars in this series have their front ends located in staggered relation. Slots 106 and 107 formed in the upper edges of the bars 90 and 91 will, in an inoperative position, be disposed in staggered relation as shown in Fig. 14. When these control bars, 60 however, are in operative position and the proper coin has been placed within the coin-control mechanism these slots will be aligned, as shown in Fig. 13, to receive the bar 105 which normally is in a position to drop into the aligned slots at 65 a predetermined point in the operation of the mechanism.

Legs 110 are secured to the outer ends of the bar 105, depend therefrom and are mounted in guides 111 carried by the side walls 21 and 21a. 70 A lever 112 (Figs. 1 to 3, inclusive) is pivotally mounted at 113 on ears 114 extending from the rear wall 11 of the housing. The upper end 115 of said lever is in a position to be engaged by a finger 116 projecting from the underface of the 75

cover 21 for moving the lever to the right in said figures. The lower end of the lever is received within a pocket 117 formed in a sliding block 118 and pivoted to said block at 119. This block is 5 slidably mounted on the partition 13. A spring 120, mounted on a pin 121 carried by a wall 122 formed at the front end of the shelf 113, is adapted to press against a shoulder 123 formed on the front end of an extension 124 of the block 10 118. The lower end of the coin slot or chute 20 is closed by a lip 125 projecting forwardly from the shoulder 123 and this lip also extends over a vertical slot 126 formed in the member 38 of the 15 slideable drawer 39. When the drawer is in the proper position the slot 126 will be in vertical alignment with the slot 20.

A trip lever 127 is pivotally mounted on a pin 128 which is carried by the side walls of the housing. This lever is provided with a finger 20 129 which projects through a slot 130 in the shelf 13 and through a slot 131 formed in the block 118 when the slot 131 aligns with the slot 130. A second finger or keeper 132 projects from the underface of the lever 127 and is adapted to normally engage the front end of the slot 131 to prevent rearward movement of the block 118 as 25 will be presently explained. The front end of the lever 127 is provided with a cross bar 133 which is adapted to be engaged by the lower ends 134 of the legs 110 which are connected to the cross bar 105.

The drawer 39 is provided with a curved slot 135 for a purpose which will be presently explained. The rear section of the drawer is provided with an elongated pocket 140 in which is mounted a spring 141 which has one end in engagement with a shoulder 142 at the rear end of the pocket while the opposite end of the spring is in engagement with a collar 143 carried by one 40 end of a slideable rod 144 which extends through a passage 145 in the rear wall 11 of the housing 10 and a disc or collar 146 is secured to the outer end of the rod and normally is engaged with the outer face of the wall 11. The spring 141 maintains the drawer 39 in its inward position. It 45 will be noted that the rod 32 (Figs. 1 to 3) projects through the passages 35 and 36 and prevents the removal of the drawer 39 when the cover plate 25 is in its downward position or is ascending towards its extreme upward inoperative 50 position. When the top reaches its upward limit of movement, as shown in Fig. 1, the rod 32 will be released from the passages 35 and 36.

The upper face of the drawer is provided with 55 a groove 150 in which the free end of the finger 129 rides at times. The rear wall 151 of this groove is shown as being inclined to act as a cam member for engaging the free end of the finger 129 for forcing the finger upwardly to release the latch member 132 of the lever 127 from its engagement with the front wall of the slot 131 formed in the reduced portion 124 of the block 118 when the drawer 39 is withdrawn.

A pair of bell crank levers 152 are pivotally 60 mounted on pintles 153 extending from the side walls 21 and 21a at opposite sides of the series of control bars 90 and 91. One arm 154 of each of the bell crank levers is adapted to be received by a slot 155 formed in the upper ends of the 65 legs 110 which depend from the cross bar 105. The free end of the other arms of the levers 152, as shown at 156, are adapted to be engaged by the inner face of the descending top 25, as shown in Fig. 2, for rocking the lever for raising the 70 cross bar 105 and the legs 110 out of engagement 75

with the cross bar 133 carried by the lever 127 so that the lever will be rocked and the latch member 132 will be moved into engagement with the front wall of the slot 131 and prevent the spring 120 from forcing the block 118 to its rearward and inoperative position after the block has been moved forwardly. 5

A pair of levers 160, shown in dotted lines in Figs. 1 to 3, inclusive, and in full lines in Fig. 5, are pivotally mounted on pins 161. Pins 162 carried by the side bars 72 of the cross bar 71 project through elongated slots 163 formed in the levers 160 so that when the block 118 is reciprocated these levers will be rocked and the free ends 164 of said levers will engage the rim or flange 63 of 15 the coin holder 60 and jar the coin holder to cause the coin to be released from the flange 62. 10

The front end of the selective bars 70, as shown more particularly in Figs. 5 and 14, are cut out or countersunk to form an intaglio into which 20 will neatly fit that face of a nickel upon which the buffalo and indicia is cast. In other words when the nickel has been dropped through the slot 20 and is in the proper position, it will neatly fit within this intaglio 170. Due to the fact, however, that it is impossible for the operator to drop the coin so that the proper face will neatly fit within the intaglio the coin is revolved until it does neatly fit. While the device is shown to be operated in connection with the depositing of a 30 nickel the intaglio may represent one face of a ten cent piece or a quarter and where there are three slots employed for the various coins in a coin-controlled telephone three of these casings 35 may be applied side by side or three mechanisms may be employed in a single casing. While it is true that the slots in a telephone box or housing are close together it will be appreciated that the widths of the members 70, 90 and 91 are restricted in width so that they can be operatively housed 40 in a very small space and the width of each of the individual members 70, 90 and 91 will be determined by the diameter of the coin employed.

In order to deposit a nickel or the proper coin into the operating mechanism the lip 30 of the 45 cover 25 must be depressed so that the rod 32 will also be depressed until the inclined portion 40 of the rod will engage the walls of the slot 33 and since the rod 32 must be moved in a vertical line the sliding plate 34 will be moved rearwardly 50 until the coin slot 34a aligns with the coin chute 20. At this time the slot 31 in the cover 25 will also be aligned with the slot 34a in chute 20 as will appear from Fig. 2. The coin then may be deposited through these aligned slots whence it 55 will fall through the chute 20 and in alignment with the inner face of the disc 60 and will rest upon the lip 125 of the slideable block 118.

As the rod 32 is moved downwardly the cam member 58 will engage the inclined walls of the 60 member 57 and force said member to the left in Figs. 1 to 3, inclusive, against the tension of the spring 54 and thus the disc 60 which is rigidly connected with said shaft will likewise be forced to the left to open the coin chute 20 and the inner 65 face of the disc 60 will be spaced from the outer faces of the bars 70 and in spaced relation with the intaglio 170. As the rod 32 is moved downwardly the rack 61 (Fig. 4) which meshes with the gear wheel 59 causes the disc 60 to be revolved 70 idly and the lower end of the rod 32 will project through the passages 35 and 36 of the drawer 39 and prevent manipulation of said drawer. It will be noted that the lower reduced end 32 of said rod 75 is provided with an elongated slot 171 received by

a pin 172 projecting from the front plate 14 will aid in guiding the rod in its downward movement and will maintain the rack in engagement with the gear wheel 59.

- 5 A number of operations are started when the cover plate 25 is moved down against the tension of the spring 27 and one of these operations is caused by the finger 116 engaging the upper end 115 of the lever 112 whereby the upper end of said lever is moved to the right in Figs. 1 to 3, inclusive, while the lower end is moved to the left. This causes the block 118 to be moved to the left whereby the latch member 132 will drop into the slot 131 and engage over the front wall of said slot 10 and 15 and prevent rearward movement of the block against the tension of the coil spring 120. By this movement the lip 125 has been moved beneath the lower end of the chute 20 to maintain the coin 175 within the slot and will prevent the coin from 20 passing through the openings 126 and 126a into the usual slot of the telephone box.
- The block 118 is moved forwardly in advance of the operation of any of the other elements because of the fact that the finger 116 is normally in engagement with the upper end 115 of the lever 112. However, the cover plate 25 must be rocked through a predetermined angle before the slidable plate 34 is moved to align the passage 34a with the chute 20 and before the levers 152 are rocked.
- 30 It must be borne in mind that if the proper coin had been placed in the chute 20 and had passed through the slots 126 and 126a into the slot of the telephone receiver housing the bar 105 would be resting within the aligned slots 106 and 107 of the control bars 90 and 91. When the cover 25 is depressed sufficiently the rear arms 156 of the lever 152 will be engaged by the top of the cover and said arms would be rocked to the right in Figs. 1 to 3, inclusive, so that the arms 154 of said 35 lever will be raised and thus they will raise the cross bar 105 out of the slots 106 and 107 of the control bars 90 and 91, so that these control bars will be free to be moved by the weights 83 and 84. When the cross bar 105 is raised the legs 110 40 depending from said cross bar will also be raised, thereby freeing the lever 127 so that the rear weighted end of said lever will tend to fall by gravity and the latch member 132 will be in a position to fall into the slot 131 of the block 118 because of the fact that the lever 112 has moved the block 118 forwardly so that the slot 131 will be in a position to receive the latch member 132. The weighted members 83 and 84 which are held by the control bars 90 and 91 will tend to fall rearwardly and rock on the pivot 82 so that the fingers 45 85 and 86 of said weights will rock forwardly and thus shift the bars 70 forwardly whereby the intaglio 172 will be in a position to press against the coin 175.
- 50 When the finger of the operator is released from the lip 30 after the cover 25 has been lowered against the tension of the spring 27, the cover will be elevated and it will rise slowly due to the fact that the air cushioned piston 48 (Fig. 1) will prevent rapid elevation of the cover. As the cover rises the rod 32 will likewise be raised and the rack (Fig. 4) will cause rotation of the gear wheel 59 and likewise the disc 60. As the bar 32 rises (Figs. 5 to 3, inclusive) the cam member 58 will be moved away from the conically-shaped member 57 so that the coil spring 54 will force the shaft 50 and the disc 60 to the right and press the coin 175 against the intaglio 170 and the coin will be 55 engaged by the annular lip 62 of said disc whereby 60
- 70 75

the coin will be revolved with the disc 60 until the inner face of the coin containing the embossed configuration of a buffalo will be neatly fitted within the intaglio. At this time the control bars 90 and 91 will be so positioned that the slots 106 and 107 will be aligned to permit the cross bar 105 to drop into said slots whereby the legs 110 will drop the cross bar 133 carried by the lever 127 and thus rock the said lever and release the latch member 132 from the slot 131 whereby the spring 10 120 will move the block 118 rearwardly and the lip 125 will likewise be moved rearwardly away from the bottom of the chute 20 to permit the coin when released to fall into the slot 126 and thus descend into the slot of the housing of the telephone receiver. As the block 118 moves rearwardly the upper ends of the levers 160 will be rocked forwardly and they will engage the flange 63 of the disc 60 and this impact will cause the coin to be released from the flange 62 of said disc so that the coin will be free to drop into the slot 126.

The bars 70, as has been explained, are moved forwardly by the tilting of the weights 83 and they will be maintained in a proper position so that all of the various sections of the intaglio which have 25 been formed in the front ends of the bars 70 will be aligned to permit one face of the coin to be neatly fitted within the intaglio.

It will be noted that when the control bars 90 and 91 and the bars 70 are in an inoperative position that the slots 106 and 107 will be out of alignment, as shown in Fig. 4, and alternate fingers 75 on the bars 70 will be moved forwardly. When the slots 106 and 107 are not in alignment the cross bar 105 cannot operate to pass the coin.

When a spurious coin, an incorrect coin, or a slug has been placed within the chute 20 it will drop into position to be engaged by the inner face of the disc 60 but due to the fact that it does not have the proper embossed configuration to be fitted within the intaglio the bars 70 will not be moved forwardly and therefore all of the weights 83 and 84 cannot be operated so that the control bars 90 and 91 will not be shifted to the proper position to permit the cross bar 40 105 to drop within the slots 106 and 107 because said slots will be out of alignment as shown in Fig. 14. Thus the fingers 75 and 76 will be in the position shown in Fig. 14 and the bars 70 will be maintained in an inoperative position 50 so that the intaglio in effect is distorted. When this happens the block 118 will be retained in the position shown in Fig. 3 since the legs 110 cannot drop downwardly to release the lever 127 and the latch member 132. The lip 125 will thus 55 be located below the lower end of the chute 20 and prevent the coin from dropping into the slot 126.

When the lip 30 is released the cover 25 will be automatically raised, thus removing the rod 32 60 from the passages 35 and 36 at the front end of the drawer 39 and it will be necessary for the operator then to pull upon the knob 39a against the tension of the spring 141 until the cam shoulder 151 engages the depending finger 129 65 of the lever 127 so that the finger will rise until it rests upon the top portion 151a of the drawer 39 at the rear end thereof whereby the latch member 132 will be released from the front wall of the slot 130 so that the spring 120 will 70 force the block 118 rearwardly and thus remove the lip 125 from below the lower end of the chute 20. At this time, however, the curved slot 135 will be in alignment with the lower end of the chute 20 and the coin will slide within 75

said curved slot and be projected beyond the free edge 12a of the bottom 12 of the housing so that the spurious coin or slug will be discharged into the booth or into the room and will never reach the slot 126 or the slot 126a which aligns with the usual coin slot of the housing of the telephone receiver.

The incorrect coin or slug will remain in the lower end of the chute 20 and be supported by the lip 125 until the drawer 39 has been moved to the left against the tension of the spring 141 and this drawer must thus be operated to permit the proper operation of the mechanism before a proper coin can be so positioned as to set the device in operation to permit the proper coin to pass through the slots 126 and 126a.

When the cover is released and if the proper coin has been inserted the finger 116 moves forwardly and upwardly away from the free end of the lever 115 to permit the spring 120 to force the block 118 rearwardly and the cross bar 105 will remain in its locked position with respect to the control bars 90 and 91 until the cover is again depressed to act upon the levers 152 for raising the control bar 105. When the cam member 58 has released the conically-shaped member 57 the spring 54 will move the disc 60 towards the front ends of the plates and when the coin has been properly engaged by the intaglio in the front ends of said plates the bars 70 will have been moved slightly to the left whereby by the weights 83 will again be adjusted to their original positions and such movement will cause the control bars 90 and 91 to be properly positioned for the alignment of the slots 106 and 107 so that the cross bar 105 will drop into said slots. As soon as the bar 105, however, has been released the weights 83 and 84 will tilt rearwardly to cause misalignment of the slots 106 and 107 and a disarrangement of the bars 70 so that the sections of the intaglio will be placed out of alignment and thus deformed.

The block 118 has side walls 118a which are guided by a cooperating means between the shelf 45 13 and said walls.

The housing or telephone box is designated by the numeral 10a and it is upon the top of this housing that the housing or housings 10 of the various coin-detecting mechanisms are supported.

50 We claim:

1. A fraud detecting device comprising a housing, a spring-pressed rotatable coin holder in the housing, a plurality of closely associated movable members having ends spaced from the holder, the combined spaced ends of said members having an intaglio representing one face of a coin formed therein, said ends being normally spaced in an irregular manner to disfigure the intaglio, means for pressing the ends of the members into engagement with the face of the coin, means for rotating the holder, manual means causing operation of the rotating means for revolving the coin and holder until the embossed configuration on one face of the coin neatly fits into the intaglio when the ends of the members will be moved into alignment, a slide retaining the coin in the housing, a spring tending to move the slide means to an inoperative position, means actuated by the manual means for moving the slide means to an operative position, means for holding the slide means in said position, a gravity-actuated means moving the holding means to an inoperative position to set free the 70 slide means for action by the spring to dis-

charge the coin, means operated by the manual means for restoring the gravity-actuated means to an inoperative position, means supporting the gravity-actuated means in an inoperative position, and means operated by the pressing means for the movable members for causing said supporting means to release the gravity-operated means when the ends of the movable members have been aligned.

2. A fraud detecting device comprising a housing, a spring-pressed rotatable coin holder in the housing, a plurality of closely associated movable members having ends spaced from the holder, the combined spaced ends of said members having an intaglio representing one face of a coin formed therein, said ends being normally spaced in an irregular manner to disfigure the intaglio, means pressing the ends of the members into engagement with the face of the coin, means for rotating the holder, manual means causing the operation of the rotating means for revolving the coin and holder until the embossed configuration on one face of the coin neatly fits into the intaglio when the ends of the movable members will be aligned, means for retaining the coin in the housing, a spring urging the retaining means to released position, a latch for holding the retaining means in an operative position, gravity-actuated means moving the latch to an inoperative position to set free the retaining means to discharge the coin, a plurality of associated supports for retaining the gravity-actuated means in an inoperative position, each support having a slot, said slots being unaligned when the intaglio is disfigured but adapted to be aligned when the intaglio fits the coin, connections between the pressing means for the members and the supports whereby the supports will be moved in unison with the movable members to align the slots, means connected with the gravity-actuated means, resting on the supports and adapted to fall into the aligned slots for lowering said gravity-actuated means onto the latch to release said latch, and means operated by the manual means for restoring the gravity-actuated means to an inoperative position.

3. A fraud detecting device comprising a housing, a spring-pressed rotatable coin holder in the housing, a plurality of closely associated movable members having ends spaced from the holder, the combined spaced ends of said members having an intaglio representing one face of a coin formed therein, said ends being normally spaced in an irregular manner to disfigure the intaglio, means urging the ends of the members into engagement with the face of the coin, means for rotating the holder, manual means causing the operation of the rotating means for revolving the coin and holder until the embossed configuration on one face of the coin neatly fits into the intaglio when the ends of the movable members will be aligned, a slide retaining the coin in the housing, a spring urging the slide to an inoperative position, means retaining the slide in an operative position, actuating means moving the retaining means to an inoperative position to set free the slide to the action of the spring to discharge the coin, means holding the actuating means in an inoperative position, said holding means having connections with the urging means for the movable members and operated simultaneously with said movable members, said holding means releasing the actuating means when the ends of the movable members 75

- have been aligned, manual means for moving the slide to an operative position, and means operated by the manual means for returning the actuating means to an inoperative position 5 on the holding means while causing the ends of the movable members to be disaligned.
4. A device for preventing unauthorized operation of a coin-controlled device comprising a housing having a coin chute, a movable closure 10 for one end of said chute, manual means moving the closure to an operative position, means having an intaglio formed therein and representing one face of a coin and forming part of the wall of the chute, said means formed of movable sections normally displaced to distort the intaglio, a rotatable holder for receiving a coin and pressing the same against the intaglio, means operated by the manual means for causing rotation of the holder, a spring urging the holder toward the intaglio, means for pressing the sections of the intaglio means toward the coin, means retaining 15 the closure in an operative position, gravity-actuated means for releasing the retaining means, a control means composed of a plurality of sections, each section having a slot, the slots in alternate sections being normally out of alignment with the slots in the other sections when the intaglio is distorted, means connecting the sections of the control means with similarly located sections of the intaglio means, a bar carrying the gravity-actuated means and supported by the control means above the slots until the slots are aligned when said bar will fall into the slots and release the gravity-actuated means, said slots being aligned when the coin has been fitted into the intaglio. 20
5. A device for preventing unauthorized operation of a coin-controlled device comprising a housing having a coin chute, a closure for one end of said chute, manual means moving the closure to an operative position, means having an intaglio formed therein representing one face of a coin and forming part of the wall of the chute, said means formed of movable sections normally displaced to distort the intaglio, a rotatable holder for receiving a coin and pressing the same against the intaglio, a spring urging the holder toward the intaglio, means for pressing 25 the sections of the intaglio means toward the coin, means retaining the closure in position, a gravity-actuated means for releasing the retaining means, and means holding the gravity-actuated means in an inoperative position linked 30 with the sections of the intaglio means and operated by said sections when one face of the coin is fitted into the intaglio, the holding means releasing the gravity-actuated means to act on the retaining means when the coin is fitted into the intaglio. 35
6. A device for preventing unauthorized operation of a coin-controlled device comprising a housing having a coin chute, a closure for one end of said chute, manual means moving the closure to an operative position, means having an 40
- intaglio formed therein representing one face of a coin and forming part of the wall of the chute, said means formed of movable sections normally displaced to distort the intaglio, a rotatable holder for receiving a coin and pressing the same against the intaglio, means operated by the manual means for causing rotation of the holder, a spring urging the holder toward the intaglio, means for pressing the sections of the intaglio means toward the coin, means retaining the closure in an operative position, gravity-actuated means for releasing the retaining means, a control means composed of a plurality of sections, each section having a slot, the slots in alternate sections being normally out of alignment with the slots in the other sections when the intaglio is distorted, means connecting the sections of the control means with similarly located sections of the intaglio means, a bar carrying the gravity-actuated means and supported by the control means above the slots until the slots are aligned when said bar will fall into the slots and release the gravity-actuated means, said slots being aligned when the coin has been fitted into the intaglio. 45
7. A fraud detecting device comprising a housing, a spring-pressed rotatable coin holder in the housing, a plurality of closely associated movable members having ends spaced from the holder, the combined spaced ends of said members having an intaglio representing one face of a coin formed therein, said ends being normally spaced in an irregular manner to disfigure the intaglio, means for pressing the ends of the members into engagement with the face of the coin, means for rotating the holder, manual means causing operation of the rotating means for revolving the coin and holder until the embossed configuration on one face of the coin neatly fits into the intaglio when the ends of the members will be moved into alignment, a spring-pressed slide for holding the coin in the housing, means actuated by the manual means for moving the slide to an operative position, means for retaining the slide in said position, actuating means moving the retaining means to an inoperative position to set free the slide to discharge the coin, cooperative means between the movable members and the actuating means to set said actuating means in operation when the ends of said movable members have been aligned, the manual means including a spring-pressed hinged cover. 50
